US00D697511S

(12) **United States Design Patent**
Andre et al.

(10) **Patent No.:** US D697,511 S
(45) **Date of Patent:** ** *Jan. 14, 2014

(54) **DISPLAY MODULE FOR AN ELECTRONIC DEVICE**

(75) Inventors: **Bartley K. Andre**, Palo Alto, CA (US); **Daniel J. Coster**, San Francisco, CA (US); **Daniele De Iuliis**, San Francisco, CA (US); **Richard Hung Minh Dinh**, San Jose, CA (US); **Phillip M. Hobson**, Menlo Park, CA (US); **Richard P. Howarth**, San Francisco, CA (US); **Jonathan P. Ive**, San Francisco, CA (US); **Kenneth Arthur Jenks**, Capitol, CA (US); **Steve Jobs**, Palo Alto, CA (US); **Duncan Robert Kerr**, San Francisco, CA (US); **Adam Duckworth Mittleman**, San Francisco, CA (US); **Shin Nishibori**, Kailua, CA (US); **Matthew Dean Rohrbach**, San Francisco, CA (US); **Douglas B. Satzger**, Menlo Park, CA (US); **Calvin Q. Seid**, Palo Alto, CA (US); **Vincent Keane Seid**, legal representative, Los Gatos, CA (US); **Christopher J. Stringer**, Woodside, CA (US); **Tang Yew Tan**, San Francisco, CA (US); **Erik Li Wang**, Redwood City, CA (US); **Eugene Antony Whang**, San Francisco, CA (US); **Rico Zorkendorfer**, San Francisco, CA (US)

(73) Assignee: **Apple Inc.**, Cupertino, CA (US)

(*) Notice: This patent is subject to a terminal disclaimer.

(**) Term: **14 Years**

(21) Appl. No.: **29/380,125**

(22) Filed: **Nov. 30, 2010**

Related U.S. Application Data

(60) Continuation of application No. 11/821,329, filed on Jun. 21, 2007, now Pat. No. 7,889,139, and a continuation of application No. 29/364,190, filed on Jun. 21, 2010, now Pat. No. Des. 634,319, which is a continuation of application No. 29/332,683, filed on Feb. 23, 2009, now Pat. No. Des. 618,678, which is a division of application No. 29/282,831, filed on Jul.

30, 2007, now abandoned, which is a continuation of application No. 29/270,887, filed on Jan. 5, 2007, now Pat. No. Des. 580,387.
